UNITED STATES PATENT OFFICE.

SOL. C. ST. JOHN, OF EDMESTON, NEW YORK.

LOCK.

Specification of Letters Patent No. 31,267, dated January 29, 1861.

To all whom it may concern:

Be it known that I, S. C. ST. JOHN, of 5
Edmeston, in the county of Otsego and
State of New York, have invented a new
and Improved Lock; and I do hereby de-
clare that the following is a full, clear, and
exact description of the same, reference be-
ing had to the annexed drawings, making a
part of this specification, in which—

10 Figure 1 is a face view of my invention.
Fig. 2 is a section of the same taken in the
line x, x , Fig. 1. Fig. 3 is a section of the
same, taken in the line y, y , Fig. 2. Fig. 4
is a section of the same, taken in the line z, z ,
Fig. 1. Fig. 5 is a detached view of the key
of the same.

Similar letters of reference indicate cor-
responding parts in the several figures.

The object of this invention is to obtain
20 a simple and compact lock, which may be
cheaply constructed and therefore generally
adopted, and still be burglar-proof or un-
pickable.

To enable those skilled in the art to fully
25 understand and construct my invention. I
will proceed to describe it.

A represents the case of the lock, which
may be of quadrilateral form, and B, is a
30 bolt which is fitted between proper guides
in the case, and allowed to work freely in
and out. At the lower side of the bolt B,
there is a rack a , into which a pinion C,
gears, as shown plainly in Fig. 3.

The pinion C, is hollow and has a spindle
35 D, fitted within it, said spindle being
allowed to slide freely in the pinion and
having a projection b , on it. Said spindle
also has on it a collar c , against which a
40 spring E, bears, said spring having a tend-
ency to keep the spindle D, forced outward
and its projection b , within either of two
recesses c, d , in a plate F, in the case A.
Both these recesses are shown in Fig. 3, one
45 by dotted lines. The spindle D, is provided
with a feather e , which fits in a recess in the
pinion, and insures the rotation of the pin-
ion with the spindle.

G is a spindle which is fitted in the hub f ,
of a circular plate H, said plate being in a
50 circular recess in a plate g, which is fitted in
the case A. This plate H, has a hole h ,
made in it, which, when said plate is turned

in the proper position will come in line with
the end of spindle D, and expose the same.

The spindle G, is provided with a projec- 55
tion h' , and it has also a shoulder i , on it,
against which a spring j , bears; said spring
having a tendency to keep the projection h' ,
in either of two recesses k, l , in the plate F,
both of which recesses are shown in Fig. 3. 60

I is a circular plate which is placed over
the plate H, and has a hole m , in it, said hole
being in a circle which corresponds with a
circle, in which the hole h , of the plate H,
is made. At the center of the plate I, there 65
is a hole n , which is in line with the spin-
dle G.

The key J, is provided with a bit o , which
corresponds in form to the end of the spin-
dles D, G. 70

The operation is as follows:—Suppose,
for instance, the lock to be in a locked state,
as shown in Figs. 1 and 3. In order to un-
lock the lock the key is inserted in the hole
75 n , of plate I, and the spindle G, forced back
until its projection h' , is behind the plate F.

The plate H, is then allowed to turn by turn-
ing the key J, and the hole h , of said plate
is brought in line with the spindle D, the
correct position or precise spot being known 80
by the spring j , forcing the projection h' , of
said spindle into the upper recess k , of plate
F. The plate I, is then turned until its
hole n , is brought in line with the hole h ,
of plate H, and the spindle D, is exposed. 85

The key J, is then pressed against the spin-
dle D, the latter forced inward until its
projection b , is behind the plate F. The
pinion C, is then turned by turning the key,
and the bolt B, thrown back, the pinion C, 90
being turned until the projection b , of spin-
dle D, enters the recess d , in plate F, as
shown in red in Fig. 3. By this arrange-
ment it will be seen that it would be almost
impossible to pick the lock, as the plate I, 95
may be provided with figures, and placed
in varying positions, so that no person but
the one who locked the lock or adjusted said
plate could turn it so as to bring its hole n ,
in line with the spindle D. This lock at the 100
same time is exceedingly simple and may be
constructed at a small expense.

The spindle D, may extend entirely
through the lock, so that the latter may be

opened from the inner side by having a knob attached to the inner end of said spindle.

Having thus described my invention what I claim as new and desire to secure by Letters Patent, is:—

The arrangement and combination of the plates H, I, spindles D, G, provided with

the projections b, h', the stationary plate F, pinion C, and bolt D, provided with the rack a, as and for the purpose herein set forth.
